UNITED STATES PATENT OFFICE

101,712

DESIGN FOR A SHOE OR SIMILAR ARTICLE

Murray Planco, New York, N. Y.

Application August 11, 1936, Serial No. 64,351

Term of patent 3½ years

To all whom it may concern:

Be it known that I, Murray Planco, a citizen of the United States, residing in New York city, in New York County, in the State of New York, have invented a new, ornamental, and original Design for a Shoe or Similar Article, of which the following is a specification, reference being had to the accompanying drawing, forming part thereof.

Figure 1 is a plan view of a shoe showing my new design.

Figure 2 is a side elevation of the shoe, partly in perspective.

The dominant feature of the present design resides in the ornamental effect obtained in a

shoe of the type shown having a high vamp portion, the shoe being provided with three gussets of apertured material, one on each side of the shoe and of the same length, and a third gusset disposed centrally of the vamp and extending from the throat of the vamp to the toe portion thereof and approximately one and one-half times the length of the lateral gussets, said gussets having rounded lower ends and also having two lengthwise rows of apertures.

I claim:

The ornamental design for a shoe or similar article, substantially as shown and described.

MURRAY PLANCO.
